HOOD ORNAMENT

Howard V. Lindbergh, Belleville, and Herbert F. Weissinger, Franklin, Mich., assignors to Kaiser-Frazer Corporation, Willow Run, Mich., a corporation of Nevada

Application March 18, 1950, Serial No. 8,614

Term of patent 14 years

(Cl. D14—18)

To all whom it may concern:

Be it known that we, Howard V. Lindbergh and Herbert F. Weissinger, citizens of the United States of America and residents respectively of the city of Belleville, county of Washtenaw, State of Michigan, and the city of Franklin, county of Oakland, State of Michigan, have invented a new, original, and ornamental Design for Hood Ornament, of which the following is a specification, reference being had to the accompanying drawing, forming a part thereof, wherein:

Fig. 2 is a side elevational view of the hood ornament illustrated in Fig. 1;

Fig. 3 is a front elevational view of the hood ornament shown in Fig. 2, as viewed from the left thereof; and

Fig. 4 is a cross-sectional view, taken substantially along the line 4—4 of Fig. 2.

We claim:

The ornamental design for a hood ornament, as shown.

HOWARD V. LINDBERGH.
HERBERT F. WEISSINGER.
